UNITED STATES PATENT OFFICE.

HENRY CLAY BORGNER, OF LEBANON, PENNSYLVANIA.

DESIGN FOR MEMORIAL MONUMENT.

Specification forming part of Design No. 7,872, dated November 24, 1874; application filed October 15, 1874.
[Term of Patent 14 years.]

To all whom it may concern:

Be it known that I, H. C. BORGNER, of Lebanon, Lebanon county Pennsylvania, have invented a Design for a United States Centennial Presidential Memorial Monument, Fountain, or Ornamental Structure, of which the following is a specification:

The nature of my design is fully represented in the accompanying photographic illustration, to which reference is made.

A represents the star-shaped blocks, layers, or forms, of which the structure is composed, arranged one upon the other in succession, and graduated in proportion in thirty-seven (37) numbers, more or less, or equal to the number of States constituting the United

States of America during the present century—that is, from A. D. 1776 to 1873—and as emblematic of the representation of the States in the Union. B B represent figures, busts, or statues of the President or Presidents of the United States, or others, and which may be placed upon the monument or fountain in any desired order.

What I claim as my invention is—

The design for a memorial monument or fountain, formed of star-shaped blocks or layers, substantially as herein described or shown.

HENRY CLAY BORGNER.
